UNITED STATES PATENT OFFICE

128,610

DESIGN FOR A FOOD MOLD OR SIMILAR ARTICLE

Marie Baker, Salem, Oreg.

Application April 22, 1941, Serial No. 100,549

Term of patent 14 years

To all whom it may concern:

Be it known that I, Marie Baker, a citizen of the United States, and a resident of Salem, county of Marion, and State of Oregon, have invented a new, original, and ornamental Design for a Food Mold or Similar Article, of which the following is a specification, reference being had to the accompanying drawing, forming a part thereof.

In the drawing:

I claim:

The ornamental design for a food mold or similar article, substantially as shown.

MARIE BAKER.
